CLAIM

The ornamental design for a cryogenic treatment chamber substantially as shown and described.

DESCRIPTION

FIG. 1 is a perspective, front, top, and right side view illustrating the design.

FIG. 2 is a front elevation view thereof.

FIG. 3 is a rear elevation view thereof.

FIG. 4 is a right side elevation view thereof.

FIG. 5 is a left side elevation view thereof; and,

FIG. 6 is a top side elevation view thereof.

The broken lines shown in Figures illustrate portions of the cryogenic treatment chamber that form no part of the claimed design.

1 Claim, 6 Drawing Sheets
